UNITED STATES PATENT OFFICE.

WILLIAM J. JOHNSON, OF ENGLEWOOD, ILLINOIS.

STILT.

SPECIFICATION forming part of Letters Patent No. 514,600, dated February 13, 1894.

Application filed March 30, 1893. Serial No. 468,328. (No model.)

To all whom it may concern:

Be it known that I, WILLIAM J. JOHNSON, of Englewood, in the county of Cook, State of Illinois, have invented certain new and useful Improvements in Stilts, of which the following is a specification, reference being had to the accompanying drawings.

The object of my invention is to produce an improved and serviceable stilt by which the step may be readily adjusted to any desired height, and by which the mechanism for fastening the stilt to the body of the wearer may be likewise adjusted to suit different people.

In the accompanying drawings, Figure 1 is a side elevation of my stilt. Fig. 2 is a front elevation thereof. Fig. 3 is a central longitudinal section, showing the relations of the different parts to the main support or pole. Fig. 4 is a detail view of the leg strap and connected mechanism.

Referring to the figures on the drawings: 1 indicates a support or pole of any suitable length and of any desirable material, preferably wood. It is provided on one side with 25 obstructions as upwardly opening notches 2 and upon the opposite side with graduated apertures 3.

4 indicates a step, preferably made of metal, and having an aperture 5 for the admission 30 of the pole and a longitudinal slot 6 for rendering it lighter and for adjusting the foot strap 7, which is, for this purpose, provided with a spreader or stretcher 8, at one end.

9 indicates a thumb screw back of the step. 35 10 indicates a thumb screw at the other end, which serves to secure a metallic spring 12 in place and also to secure the end of the foot strap, as illustrated.

In practice, the step is slipped over the end 40 of the pole and is adjusted in place by the slipping of the spring into the notches 2, provided for it. The thumb screw 9 may be employed as a means of assisting the firm adjustment of the step when in place. When 45 mounted upon the pole, the front edge of the recess 5, of the step is firmly secured against the side of the pole, so that the spreader of the foot strap is secured firmly in place and that part of the device is ready for use.

50 When it is desired to adjust the step, all

that is necessary is to loosen the thumb screw 9, and to slip the step into the required position.

13 indicates a frame or box adapted to fit closely to the pole. It is provided in its rear wall with a thumb screw 14, which, entering the apertures 3, serves to adjust the box in any required position upon the pole. The front of the box is provided with a plate 15 in which is a dove-tailed recess 16.

17 indicates a leg strap plate provided with a dovetailed projection 18 adapted to fit into the recess in the plate and to be securely fastened therein against dislodgment by a lateral strain upon it. Upon the leg plate is secured 65 by any suitable means, as by rivets, a leg strap 19, provided with suitable fastening mechanism, as for instance, a buckle 20.

In practice, when the step has been adjusted to the required height and the box has been 70 in like manner adjusted to suit the convenience of the wearer, the leg strap is bound upon the leg of the wearer. In adjusting the stilts all that is necessary for him to do is to put his foot upon the step and slip the dove-tailed projection upon the leg plate into the dove-tailed recess in the box plate, when the device is firmly secured in place. In removing the stilts all that is necessary is to remove 75 the foot and slip the dove-tailed projection 80 on the leg plate out of the recess.

I do not confine myself to the details of construction herein described, because they may be varied in many respects without departing from the scope of my invention.

What I claim is—

1. In a stilt, the combination with a pole having obstructions, a step movable thereon, a spring upon the step adapted to engage with the obstructions, a recess in the step for the admission of the pole, a strap secured to the outer end of the step and having a spreader adapted to enter the recess and to be secured therein against the pole, when the step is secured in place, substantially as specified.

2. In a stilt, the combination with a pole provided with obstructions, of a step having a spring to engage the obstructions, a recess in the step for the reception of the pole, and a set screw in the rear of the recess to assist 95 100

in the adjustment of the step upon the pole, substantially as and for the purpose specified.

3. In a stilt, the combination with a pole and step, of a box adjustable upon the pole, 5 a leg strap thereon, and a set screw in the box whereby it may be securely adjusted upon the pole, substantially as specified.

4. In a stilt, the combination with a pole, of a box adjustably secured thereon, a dove-tailed recess in the face of the box, and a leg 10 plate provided with a dove-tailed projection and a strap, substantially as and for the purpose specified.

5. In a stilt, the combination with a pole, 15 of an adjustable box, and a leg strap, and de-

tachable connecting mechanism, substantially as specified.

6. In a stilt, the combination with the pole provided with graduated recesses, and step, of a box movable upon the pole and provided 20 with a leg strap, and adjustable mechanism upon the box adapted to engage the recesses, substantially as specified.

In testimony of all which I have hereunto subscribed my name.

WILLIAM J. JOHNSON.
